Primary Examiner — Robert M Spear*Assistant Examiner* — Darcey E Heflin*(74) Attorney, Agent, or Firm* — The Webb Law Firm(57) **CLAIM**

The ornamental design for a blocking closure for container, as shown and described.

DESCRIPTION

FIG. 1 is a top front perspective view of a blocking closure for container in accordance with the present invention.

FIG. 2 is a bottom rear perspective view of the closure.

FIG. 3 is a front view of the closure.

FIG. 4 is a right side view of the closure.

FIG. 5 is a left side view of the closure.

FIG. 6 is a top view of the closure; and,

FIG. 7 is a bottom view of the closure.
